UNITED STATES PATENT OFFICE.

CHARLES DITTMAR, OF CINCINNATI, OHIO.

DESIGN FOR A GRAPHOPHONE.

57,594.

Specification for Design.

Patented Apr. 26, 1921.

Application filed September 22, 1920. Serial No. 412,104. Term of patent 3½ years.

To all whom it may concern:

Be it known that I, CHARLES DITTMAR, a citizen of the United States, residing at Cincinnati, in the county of Hamilton and State of Ohio, have invented a new, original, and ornamental Design for Graphophones, of which the following is a specification, reference being had to the accompanying drawing, forming part thereof.

The figure is a perspective view of a graphophone, showing my new design.

I claim:

The ornamental design for a graphophone, as shown.

CHARLES DITTMAR.
